United States Patent Office

Des. 204,090
Patented Mar. 15, 1966

204,090

JOURNAL GAGE

George L. Marshall, Warwick, R.I., assignor to Central
Tool Company, Cranston, R.I., a corporation of Rhode
Island

Filed Apr. 26, 1965, Ser. No. 84,948

Term of patent 14 years

(Cl. D52—6)

FIG. 1

FIG. 2

FIG. 3

FIG. 4

FIG. 5

FIG. 1 is a perspective view of a journal gage, showing my new design;

FIG. 2 is an elevational view taken from the left end thereof;

FIG. 3 is an elevational view taken from the right end thereof;

FIG. 4 is a top plan view thereof; and

FIG. 5 is a rear elevational view thereof.

I claim:

The ornamental design for a journal gage, substantially as shown.
